BEDSPRING SUPPORT

Edmond E. Jacob, Pontiac, Mich.

Application October 2, 1946, Serial No. 700,645

8 Claims. (Cl. 5—310)

1

This invention relates to means for converting a bed spring into a bed and in particular relates to individual leg supports adapted to be secured in fixed position to the bed spring so as to elevate the same and provide a bed.

An object of the present invention is to provide supporting legs adapted to be easily installed beneath a bed spring or coil spring mattress and attached to the marginal base frame thereof, whereby the bed spring may be readily and inexpensively converted into a bed without necessitating the use of conventional bulky and heavy bed frames which are difficult to handle and usually require considerable time and effort to assemble and knock down.

A further object of the invention is to provide a simple, economical and sturdy means for converting any conventional coil spring mattress or bed spring into a bed such, for example, as a studio couch, Hollywood bed or day bed, said means comprising a number of leg members adapted to be arranged conveniently and at suitable points beneath the marginal angle frame of the bed spring and rigidly secured thereto by means of clamping devices on the upper ends of the leg members cooperable with the frame of the bed spring.

Another object of the invention is to provide individual leg supports for a bed spring having improved and novel clamping devices capable of permitting easy installation of the leg supports beneath the frame of the bed spring at any desired points along the sides thereof. The improved construction is such that the bed spring with the leg supports installed thereon becomes a conveniently useable and relatively light bed structure, easily handled and moved about, and which may be quickly knocked down when not in use with the leg supports capable of being detached and stored in a minimum of space.

Other objects of this invention will appear in the following description and appended claims, reference being had to the accompanying drawings forming a part of this specification wherein like reference characters designate corresponding parts in the several views.

Fig. 1 is a perspective view illustrating a bed spring supported and clamped in position on a series of individual legs in accordance with the present invention.

Fig. 2 is an enlarged vertical section taken substantially through lines 2—2 of Fig. 1 looking in the direction of the arrows.

Fig. 3 is a rear elevation of the construction shown in Fig. 2.

2

Fig. 4 is a perspective view of one of the legs carrying clamping means for clamping the leg in fixed position to the bed spring frame.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the drawings I have illustrated, by way of example, one embodiment of the invention in which a conventional bed spring 10 is adapted to be supported in an elevated position by means of individual leg supports which carry clamping devices at their upper ends by means of which the bed spring may be converted into a bed. The bed spring or spring mattress 10 which, in accordance with the invention, is to be supported in desired position above the floor, may be of any conventional type, such as the open coil spring structure illustrated in Fig. 1. This particular spring or spring mattress 10 comprises the usual individual coil springs 11 connected around the upper edge of the structure by means of the usual framing or border wire 12. The coil springs in the type of spring mattress shown in Fig. 1 are mounted on interconnected transverse and longitudinally extending strips in the usual manner which at their ends are attached to the bottom rectangular frame of the bed spring. This frame may be of angle iron construction comprising spaced longitudinal members 13 and transverse end members 14.

As illustrated in Fig. 1, the bed spring 10 is supported along each side thereof by means of three longitudinally spaced supporting units or leg supports which are identical in construction and generally indicated at 15. Each leg support 15 comprises a leg member 16 which may be formed either of wood or metal and which carries at its upper end a clamping device by means of which the leg support may be readily and conveniently attached at the desired locality to one of the side rails or frame members 13 of the spring mattress structure.

Each clamping device in the present instance comprises a channel shaped metallic clamp support 17 which embraces the upper inner corner of the leg 16 and accordingly comprises a top horizontal web 17a resting upon the upper end of the leg, a vertical web 17b which extends along

3

the inner side of the leg, and integral spaced side flanges 17c which engage opposite sides of the leg. Thus, the clamp support 17 in each instance engages the upper end of the associated leg 16 and embraces three vertical sides thereof 5 thereby providing a means for holding the leg firmly in position. The opposite side flanges 17c of the clamp support are secured at their upper ends to the leg 16 by means of screws 18, and the lower ends of these flanges are secured to 10 the leg by means of screws 19 having their shanks extending through curved slots 20 in the flanges. The slots 20 in the side flanges of each clamp support have their centers of curvature at the longitudinal axis of the screws 18 whereby, upon 15 loosening the screws 19, the clamp support may be adjusted a limited distance angularly about the axis of the screws 18 so as to vary the angular relation of the leg 16 to the clamp support.

The clamping device for each leg comprises a 20 vertically extending clamping member 21 which is swivelled or pivoted at its lower end to the support 17 by means of a bolt or screw 22 threaded into a screw boss 23 formed on the flange 17b of the clamp support. The upper end of the 25 clamping member 21 is bent inwardly and upwardly to provide an angularly extending portion 21a which is provided with an open-ended slot 24 adapted to receive the shank of a bolt 25. When the bolt is in assembled relation to the 30 clamping member 21, as shown in Fig. 2, the head 25a of the bolt engages the lower face of the inclined portion 21a.

The clamping device for each leg also comprises an upper horizontal clamping member 26 which terminates at its inner end in an upwardly and inwardly extending bent portion 26a which is adapted to extend in opposed parallel relation to the angular portion 21a of the clamping member 21. The portion 26a has a hole to receive the shank of the bolt 25, and threaded onto the upper end of the latter is a wing nut 27. The outer end of the clamping member 26 terminates in a return bent portion 26b which preferably extends integrally from the outer edge of the top web 17a of the clamp support.

When it is desired to assemble the leg support in supporting relation to the side rail 13 of the bed spring the wing nut 27 is loosened so as to loosen the bolt 25 in the slot 24, whereupon the vertical clamping member 21 is swung laterally and downwardly about its pivotal connection 22 to the position shown in dotted lines in Fig. 3. The bolt is then shifted upwardly to position the head 25a thereof proximate to the bent portion 26a of the upper clamping member. The leg support may then be shifted inwardly and assembled on the rail 13 with the flange 13a of the rail positioned against the inner side of the clamp support and the upper flange 13b of the rail laying within the space between the clamping member 26 and the top web 17a of the clamp support, as shown in Fig. 2. When the leg support is thus assembled with the rail 13 of the bed spring the clamping member 21 is swung upwardly from its dotted line position in Fig. 3 to its full line position, causing the shank of the bolt 25 to mesh in the slot 24. The wing nut may then be drawn down on the threaded shank of the bolt to draw the clamp portions 21a and 26a together, thereby causing the horizontal and vertical portions of the clamping members to grip tightly the flanges of the rail 13. In the event, after attaching all six legs to the frame members or rails 13 of the bed spring, any of the legs do not stand straight

5 in a vertical direction due to any irregularity of the angle iron frame 13 or for any other reason, then it is merely necessary to loosen the screws 19 and straighten the leg into proper position. This angular adjustment of each of the legs is permitted, as previously described, by reason of the adjusting slot 20. Upon adjustment of the leg the screws 19 are tightened so as to maintain the clamp support 17 in rigid position with respect to the leg.

I claim:

1. Means for converting into a bed a bed spring of the type including longitudinal side rails and a spring structure carried thereby, including a leg adapted to extend vertically beneath a side rail, a clamp support secured to the upper end of the leg and upon which the side rail is adapted to rest, a horizontal clamping member connected to the support and engageable with the top of the side rail, a vertical clamping member connected to the support and engageable with a side of the rail, a bolt connecting adjacent portions of said clamping members, and a nut threaded onto the end of the bolt and adapted to be tightened to draw said portions together.

2. Means for converting into a bed a bed spring of the type including longitudinal side rails and a spring structure carried thereby, including a leg adapted to extend vertically beneath a side rail, a clamp support secured to the upper end of the leg and upon which the side rail is adapted to rest, a horizontal clamping member connected to the support and engageable with the top of the side rail, a vertical clamping member connected to the support and engageable with a side of the rail, said members having opposed angularly and inwardly projecting portions, a bolt connecting said portions, and a nut threaded onto the end of the bolt for drawing said portions together.

3. Means for converting into a bed a bed spring of the type including longitudinal side rails and a spring structure carried thereby, including a leg adapted to extend vertically beneath a side rail, a clamp support secured to the upper end of the leg and upon which the side rail is adapted to rest, a horizontal clamping member connected to the support and engageable with the top of the side rail, a vertical clamping member connected to the support and engageable with a side of the rail, said members having inwardly projecting portions extending in opposed relation, and means for drawing said portions together to cause said members to clamp the rail.

4. Means for converting into a bed a bed spring of the type including longitudinal side rails and a spring structure carried thereby, including a leg adapted to extend vertically beneath a side rail, a clamp support secured to the upper end of the leg and upon which the side rail is adapted to rest, means for adjusting said support angularly relatively to said leg, a horizontal clamping member connected to the support and engageable with the top of the side rail, a vertical clamping member connected to the support and engageable with a side of the rail, and means for drawing said clamping members together to clamp the rail to said support.

5. Means for converting into a bed a bed spring of the type including longitudinal side rails and a spring structure carried thereby, including a leg adapted to extend vertically beneath a side rail, a clamp support secured to the upper end of the leg and upon which the side rail is adapted to rest, a horizontal clamping member connected

to the support and engageable with the top of the side rail, a vertical clamping member pivotally connected at its lower end to the support and engageable with a side of the rail, a bolt connecting adjacent portions of said clamping members, and a nut threaded onto the end of the bolt and adapted to be tightened to draw said portions together, said bolt extending through an open ended slot in said portion of the vertical clamping member to permit disconnection of the latter from the bolt when loosened.

6. Means for converting into a bed a bed spring of the type including longitudinal side rails and a spring structure carried thereby, including a leg adapted to extend beneath a side rail in supporting relation thereto, a clamp support embracing the upper inner corner of the leg and upon which said side rail is adapted to rest, a horizontal clamp member connected to the support and engageable with the top of the rail, a vertical clamp member swiveled adjacent its lower end to said support at the inner side thereof and engageable with the inner side of said rail, the inner end of said horizontal clamp member having an upwardly bent portion and the upper end of said vertical clamp member having an inwardly bent portion, and threaded means detachably connecting said bent portions and adjustable to draw the clamp members against said rail.

7. Means for converting into a bed a bed spring of the type including longitudinal side rails and a spring structure carried thereby, including a leg adapted to extend beneath a side rail in supporting relation thereto, a clamp support embracing the upper inner corner of the leg and upon which said side rail is adapted to rest, means for adjustably connecting said clamp support to said leg, a horizontal clamp member connected to the support and engageable with the top of the rail, a vertical clamp member swiveled adjacent its lower end to said support

at the inner side thereof and engageable with the inner side of said rail, the inner end of said horizontal clamp member having an upwardly bent portion and the upper end of said vertical clamp member having an inwardly bent portion, and threaded means detachably connecting said bent portions and adjustable to draw the clamp members against said rail.

8. Means for converting into a bed a bed spring of the type including longitudinal side rails and a spring structure carried thereby, including a leg adapted to extend beneath a side rail in supporting relation thereto, a clamp support embracing the upper inner corner of the leg and upon which said side rail is adapted to rest, a horizontal clamp member having a return bent portion at its outer end integral with the top of said support and spaced therefrom to engage the top of the rail, a vertical clamp member swiveled adjacent its lower end to said support at the inner side thereof and engageable with the inner side of said rail, the inner end of said horizontal clamp member having an upwardly bent portion and the upper end of said vertical clamp member having an inwardly bent portion, and threaded means detachably connecting said bent portions and adjustable to draw the clamp members against said rail.
